CLAIM

The ornamental design for a disc golf target, as shown and described.

DESCRIPTION

FIG. 1 is a perspective view of a disc golf target.

FIG. 2 is a front elevation view of the disc golf target.

FIG. 3 is a rear elevation view of the disc golf target.

FIG. 4 is a left side elevation view of the disc golf target.

FIG. 5 is a top plan view of the disc golf target.

FIG. 6 is a bottom plan view of the disc golf target.

FIG. 7 is another left side elevation view of the disc golf target; and,

FIG. 8 is an enlarged view of the portion “8” shown in FIG. 7 for showing portions of the article illustrated with broken lines.

The right side elevation view of the disc golf target is omitted because the right side elevation view is the mirror view of the left side elevation view shown in FIG. 4.

In the drawings, broken lines are for the purpose of illustrating portions of the disc golf target that form no part of the claimed design.

In FIG. 7, a circle, a number “8” and an indicating line are for the purpose of defining the portion “8” and form no part of the claimed design.
